UNITED STATES PATENT OFFICE.

DANIEL L. TOWER, OF BROOKLYN, NEW YORK.

SAFETY-LOCK FOR FIRE-ARMS.

SPECIFICATION forming part of Letters Patent No. 305,866, dated September 30, 1884.

Application filed January 5, 1884. (No model.)

To all whom it may concern:

Be it known that I, DANIEL L. TOWER, of Brooklyn, in the county of Kings and State of New York, have invented a new and useful 5 Improvement in Safety-Locks for Fire-Arms; and the following is declared to be a description of the same.

The object of this invention is to combine with the hammer and trigger a safety-catch 10 that acts to prevent the hammer being raised until the trigger is moved and prevents the hammer descending, except after the trigger has been pulled and the safety-catch moved away from the stop or notch. I accomplish 15 these by the mechanism hereinafter described.

My improved fire-arm is constructed with a safety-catch pivoted upon a pin in the stock of the arm. One portion of the safety-catch engages a pin upon the hammer, when the 20 said hammer is down "home" in the position immediately after firing a cartridge, and prevents the hammer being pulled back either accidentally or from other cause. Another portion of the safety-catch is so constructed 25 that the operation of the trigger in cocking the arm first moves the safety-catch, disengaging that portion of it that is in contact with the pin upon the hammer. The further movement of the trigger cocks the hammer pre- 30 paratory to firing. The safety-catch is also constructed with a sear that will engage a notch in the hammer, and retain said hammer in the position of "half-cock," when desired.

My invention further relates to a safety- 35 slide under the trigger-spring that can be operated by hand to engage a notch in the trigger and lock the same, preventing it being accidentally moved. This safety-slide is used to lock the trigger when in its normal condition.

In the drawings, Figure 1 is an elevation of the arm and operating parts, a portion of the metal shell being removed. Fig. 2 is a plan of the hammer tumbler-trigger and safety- 45 catch. Fig. 3 is an elevation of the operating parts in the position of half-cock. Fig. 4 illustrates a modification.

The hammer *a*, its operating-spring *a'*, the trigger *b*, its spring *b'*, and the dog *c*, for re- 50 volving the cylinder of cartridge-chambers, together with the stock and barrel of the fire-

arm, are of the usual construction employed in self-cocking revolvers.

The safety-catch *d* is of the shape shown in Figs. 1 and 3, and it is made as one piece, 55 with the sear *e* and tail-piece *e'*, and is pivoted upon a screw or a stud, *l*, in the housing of the lock.

In the position shown in Fig. 1 the safety-catch *d* at one end engages the pin *i* upon the 60 tumbler portion of the hammer *a*, and any attempt to move the hammer back by grasping the top of said hammer is prevented by the pin *i*. The other end of the safety-catch *d* in this position rests upon the inclined projec- 65 tion *c'* upon the dog *c*.

The trigger *b* can be locked by the safety-slide *l*, being pushed by hand into the notch into the trigger at 2. The trigger-spring *b'* applies a friction or pressure to hold the slide 70 *l* in any position to which it may be moved.

The trigger must be liberated by pushing back the slide *l* before the arm can be fired. When the trigger *b* is moved, its dog *c* trips the safety-catch *d*, removing its end from 75 contact with the pin *i* upon the hammer, and thus liberating the hammer. The further move-

ment of the trigger causes the finger *S* to act upon the hammer-tail *t* and move it to the position of half-cock, (shown in Fig. 3,) where, 80 if desired, the sear *e* will engage a notch upon the hammer-tumbler and hold it. The fur-

ther movement of the trigger to fire the arm throws the hammer back still farther, and at the same time a pin, *3*, in the trigger *b* tilts 85 the tail-piece *e'* and sear *e* and the safety-catch *d* and holds them away from the hammer while said hammer is descending to fire the arm. When the hammer reaches its nor- 90 mal position and the trigger is released, the spring *d'* returns the safety-catch *d* to the po- sition shown in Fig. 1, locking the hammer as before.

In the modification shown in Fig. 4 a pro- 95 jection, *i'*, on the hammer-tumbler takes the place of the pin *i* the sear *e* is made of a modified shape, and the safety-catch *d* is formed of one even piece of metal composed of the sear *e*, tail-piece *e'*, and end acted upon by the inclined portion *c'*. In this case the inclined 100 portion *c'* is upon the trigger *b* instead of upon the dog *c*. The sear *e* in this case is tilted

when the trigger is pulled and frees the projection i' ; and at half-cock, the sear catching behind it, the operations of the parts are the same as heretofore described.

5 I do not wish to be understood as limiting my invention to revolving fire-arms or self-cocking revolvers, as the devices heretofore described might be applied to any character of pistol or gun.

10 I claim as my invention—

The combination, with the hammer and trigger, of a safety-catch intervening between the hammer and the trigger, and being moved

by said trigger, and stops upon the hammer, against which the safety-catch operates, substantially as specified, whereby the hammer cannot be cocked until the trigger has been moved, and the safety-catch also prevents the hammer descending until the trigger is moved, as set forth.

Signed by me this 31st day of December, 20
A. D. 1884.

DANL. L. TOWER.
